UNITED STATES PATENT OFFICE.

ALBERT E. REAM, OF BRAYMER, MISSOURI, ASSIGNOR OF ONE-HALF TO ELLA REAM, OF BRAYMER, MISSOURI, AND ONE-HALF TO EDWARD A. REAM, OF BRAYMER, MISSOURI.

ANTISKID CHAIN.

Application filed March 23, 1925. Serial No. 17,721.

To all whom it may concern:

Be it known that I, ALBERT E. REAM, a citizen of the United States, residing at Braymer, in the county of Caldwell and State of Missouri, have invented certain new and useful Improvements in Antiskid Chains, of which the following is a specification.

My invention relates to antiskid devices 10 for application to the tires of motor vehicles, and one object is to provide a simple and durable device of this character which may be stamped from sheet metal at small cost.

A further object is to provide devices of 15 this character which, in one form, will present substantially continuous surfaces to the road and thereby overcome the jolting effect imparted to the motor vehicle by the transverse links of the conventional nonskid 20 chains.

Another object is to arrange the road-engaging elements of the device in a manner to effectively prevent skidding in any direction.

25 In order that the invention may be fully understood, reference will now be had to the accompanying drawing, in which:

Fig. 1 is a fragmentary side elevation of 30 a motor vehicle wheel equipped with the nonskid device.

Fig. 2 is a broken inverted plan view of the nonskid device detached from the wheel.

Fig. 3 is a fragmentary perspective view 35 of a portion of the device.

Fig. 4 is a fragmentary side elevation of a wheel equipped with a modified form of the device.

Fig. 5 is a cross section on line V—V of 40 Fig. 4 of the device removed from the wheel.

45 Referring now more particularly to the form disclosed by Figs. 1 to 3, inclusive, 2 designates a metal strip of suitable length having blades or road-engaging members 4 and 5 projecting substantially at right-angles from its longitudinal margins. The

blade 4 are spaced apart and certain edges 6 thereof lap portions of the spaces 7 between the blades 5, while edges 8 of the latter blades lap portions of the spaces 9

50 of the blades 4 to present a substantially continuous surface 10 to the road, so that the devices will not cause jolting of the vehicle such as occurs when running on a hard surfaced road with the conventional non-

55 skid chain provided with transverse links.

The edges 6 and 8 are also included in opposite directions from each other to form points or spurs 11 and 12, respectively, the former of which are adapted to engage in the surface of the road and check the wheel 60 A, on application of the brakes, when the vehicle is traveling in the direction of the arrow a, Fig. 1, while the spurs 12 are adapted to engage in the surface of the road on application of the brakes when the vehicle is traveling in a reverse direction to said arrow a.

From the foregoing it will be understood that the wheels of the vehicle will be held 65 from skidding irrespective of whether the vehicle is traveling forward or backing up. It is also immaterial whether the spurs 11 or 12 point in the forward direction, and hence care need not be exercised in applying the devices to the wheels. In addition 70 to the spurs 11 and 12 preventing skidding in a direction longitudinally of the strip 2, the road-engaging edges 14 and 15 of the blades 4 and 5, respectively, prevent lateral 75 skidding to either side, and hence skidding in all directions is effectually overcome.

When the device is arranged to extend 80 longitudinally around the periphery of the tire B as shown by Fig. 1, a pair of strips 2 are preferably employed and connected by 85 transverse chains 16, which are not intended to engage the surface of the road unless the same is sufficiently soft to permit the blades 4 and 5 to sink to the depth of said chains 16. The chains 16 are of sufficient length to 90 straddle the transverse arch of the tire tread, so that the strips 2 will be positioned far enough from opposite sides of a center line 95 extending around the tire B to prevent lateral displacement of said strips 2, and if found desirable said strips 2 may be anchored in any conventional way to the wheel 100 spokes C.

Any suitable means may be employed for 105 connecting the ends of the strips 2. In the drawing, I have shown one end of each strip provided with a link 18, while its opposite end is equipped with the conventional hook 20 for detachably engaging said link 18.

In the form disclosed by Figs. 4 and 5, 110 the metal strips 2^a extend across the tread of the tire B, and each strip 2^a is provided at its ends with hooks 22 for detachably engaging chains 24, which extend around on each side of the tire B' and are detachably

connected at their ends by links 18^a and hooks 20^a. The strips 2^a like the strips 2 are equipped along their longitudinal margins with blades 4^a and 5^a similar in form to the blades 4 and 5, respectively.

From the foregoing description it is apparent that I have provided antiskid devices embodying the advantages above pointed out, and while I have shown two forms of said devices I reserve the right to such other forms as properly fall within the spirit and scope of the invention as claimed.

Having thus described my invention, what I claim and desire to secure by Letters Patent, is:

1. In a device of the character described, a member consisting of a flexible metallic strip of sufficient length to extend almost entirely around the periphery of a tire, spaced blades formed integral with and projecting at substantially right angles from the longitudinal margins of said strip and outwardly beyond the periphery of the tire, the edges of said blades being inclined at an angle to the body of the strip, and means for detachably connecting the ends of said strip.

2. In a device of the character described, a member consisting of a flexible metallic strip of sufficient length to extend almost entirely around the periphery of a tire, spaced blades projecting at substantially right angles from the longitudinal margins of said strip and outwardly beyond the periphery of the tire, the blades at one margin having edges inclined in an opposite direction from edges of the blades at the opposite margin, and means for detachably connecting the ends of said strip.

3. A device of the character described consisting of a pair of metallic strips each of sufficient length to extend almost entirely around the periphery of the tire, spaced blades projecting at substantially right angles from the longitudinal margins of said strips the blades at one margin lapping the spaces between the blades at the opposite margin, means for detachably connecting the ends of said strips, and transverse members connecting said pair of strips.

In testimony whereof I affix my signature.

ALBERT E. REAM.
